UNITED STATES PATENT OFFICE.

GEORGE HIGGINSON, OF LONDON, ENGLAND.

AERATING AND BOTTLING APPARATUS.

No. 870,103.

Specification of Letters Patent.

Patented Nov. 5, 1907.

Application filed February 6, 1906. Serial No. 299,703.

To all whom it may concern:

Be it known that I, GEORGE HIGGINSON, of 1 and 2 Ham Yard, Piccadilly Circus, in the county of London, England, mechanical engineer, have invented certain 5 new and useful Improvements in and Relating to Aerating and Bottling Apparatus, of which the following is a specification.

This invention relates to aerating and bottling apparatus and has for its object to provide a simple machine 10 for aerating liquids and bottling the same.

Apparatus for aerating and bottling liquids made in accordance with this invention comprises a chamber adapted to be filled with water and with or without a second chamber adapted to be filled with syrup, a frame 15 containing a bottle and adapted to be rotated in the plane of the longitudinal axis of the bottle, means for supplying the first chamber with water and the second, when required, with syrup, and valves for controlling the same, a gas supply leading to the first chamber and 20 a valve controlling said supply and valves and passages adapted to lead said gas supply through the first chamber and through the second chamber where employed to the mouth of the bottle and when desired to a pneumatic pad or other means for holding the bottle in said 25 bottle frame and also for operating a bottle guard while the bottling is taking place.

Referring now to the drawings—Figure 1 is a sectional elevation of an apparatus made in accordance with the invention. Fig. 2 is a side elevation of Fig. 1 30 looking in the direction of the arrow, parts being broken away. Fig. 3 is a plan of Fig. 1 part 1 being in section on line A—A of Fig. 1. Fig. 4 is a plan of the disk valve 4. Fig. 5 is a plan of the frame showing the seating of the disk valve 4. Fig. 6 is an elevation of the 35 frame showing the seating of the disk valve 7. Fig. 7 is a similar view to Fig. 6 showing the disk valve. Fig. 8 is a sectional plan of part of Fig. 1 showing the bottle guard.

In the drawings, which show an apparatus fitted with 40 a syrup chamber, 1 is the fixed frame of the machine, on the upper side of which is mounted a measuring vessel divided into chambers 2, 3 for water and syrup respectively. Between the lower face of the said measuring vessel and the frame 1, is disposed a rotary disk 45 valve 4 provided with ports, which, when the disk is rotated by the handle 5 make the necessary connections between the gas water and syrup supplies, and the chambers 2 and 3 and the bottle or container to be filled as hereinafter fully set forth.

50 6 is a frame or holder in which the bottle A to be filled is carried, which is formed in one with another rotary valve or disk 7 mounted upon the frame 1 at right angles to the first mentioned disk 4, which valve 7 together with the bottle supporting frame 6 is adapted 55 to be rotated by means of the handle 8.

For the sake of clearness I will first describe the vari-

ous ports of the disk valves 4 and 7 and their respective functions.

Referring first to the disk 4, this as will be seen from Fig. 3 is adapted to be moved by the handle 5, from 60 the position shown to that indicated by the line x. In the position shown, a port 9 in the valve, is adapted to open communication with the chamber 2 from the gas supply 10 while chamber 3 is also in communication with 2 by the port 11, the port 12 in the disk serving 65 to establish connection from the said chambers to the bottle A. 13 is a branch duct from the port 9, which, in conjunction with the port 14 in the frame 1 allows passage of gas to a pneumatic pad or holder hereinafter referred to. 15 is a passage in the valve 4 adapted when 70 same is turned, to be brought into alignment with the water supply 16 and the chamber 2, whereby said chamber is filled; at the same time an overflow or waste pipe 17 provided in the chamber 2 is adapted to be opened to the pipe 18 by a port 19 in the disk 4. Snift ports 20 75 are also provided in the disk, slightly in advance of 19 whereby the gas may be snifted from the chamber 2 during the act of moving the disk 4. When the disk 4 is moved to allow water to enter the chamber 2 from the supply 16 through port 15, syrup enters the chamber 3 from the supply 21 through a port 22 in the disk. 23 is a duct (shown more particularly in Fig. 4) adapted when the disk is traveled to open communication with the atmosphere through port 24 in the frame 1 from the port 14. A passage 25 is provided in the frame 1 leading to the second disk valve 7 adapted, when the ports are in the position shown in Fig. 1 to make connection with the chamber 3 by the duct 12 in the valve 4. 26, Figs. 1 and 6 is a duct connecting the valve 7 with the waste pipe 18, and opposite which the passage 28 is arranged to come in the rotation of the valve 7 so as to snift off the pressure from 28 to the atmosphere through the pipe 18 at the required time. 27, Fig. 4 is a branch passage having one opening on the upper side and two openings on the underside of the disk 4 which duct 27 90 during the movement of the valve 4 allows the pressure in the passage 25 to be snifted off through the pipe 18 in the frame.

Referring now to the disk valve, 7, 28 is a passage leading from the bottle mouth and having a port in the 100 valve 7 adapted to co-act with the branched duct 29 in the frame 1 which communicates by the passage 28a in the disk 7, with the passage 25, whereby when the parts are in position, Fig. 1, the aerated mixture is delivered to the bottle A. Passages 30, 31 in the valve 7 105 and frame 1 respectively also serve to connect the passage 14 to the passage 32 in bottle holder 6. This passage 32 is formed in the upper part of the rotary frame 6 and communicates with the pneumatic pad or holding device 33 for supporting the bottle A. This passage 110 32 is adapted to supply gas to the said pneumatic pad when the parts are in the position shown in Fig. 1.

- The various ports and passages in the disk valves 4 and 7 are provided with cup shaped packers such as 34 whereby a tight joint is secured between the moving parts.
- 5 The rotary frame 6 is provided with a resilient cup 35 for receiving the mouth of the bottle, while the other end of the bottle is supported by the aforementioned pneumatic pad 33. This consists of a pad of india rubber or like material which forms one wall of a chamber 10 37 which chamber is adapted to be supplied with gas as above described from the passage 32, the gas serving to press the pad 37 onto the end of the bottle and effectually hold the same

In some cases the gas pressure may be used for operating means for inclosing the bottle during the bottling operation, in a cage or guard. This guard which is shown more particularly in Fig. 8, is comprised by two semi-circular shield plates 38 and 39; the one 38 being rigidly connected to the frame 6 as at 40, while the 20 other plate 39 is attached to rings 41, 42 at top and bottom and adapted to be rotated to entirely inclose the bottle and prevent damage in case same should burst. This rotary movement of the plate 39 is effected by gas pressure for which purpose a plunger 43 pressed by a 25 spring 44 is disposed in the frame 6 and adapted to project into the chamber or space 37 above the pad 33. The plunger 43 is provided with a cam groove 45 which coacts with a pin or projection 46. The plunger 43 is also provided with an enlarged head 47 which is covered by a flexible diaphragm or cover 48 so formed as to allow the reciprocation of the plunger without stretching the same. This cover 48 serves to form the upper 30 wall of the chamber 37.

Surrounding the outside of the plunger 44 is mounted 35 a collar 49 which carries the pin or projection 46, adapted, when the plunger is reciprocated to be rotated to operate the said semi-circular cover 39 by means of an arm 50 attached thereto. In the drawing the end of the said arm 50, where same is fitted into the collar 40 49 is projected therethrough and forms the pin 46, whereby the arm 50 and collar 49 is rotated by the reciprocation of the plunger 43.

It is obvious, that the plunger 43 must not rotate during its reciprocation, and in order to prevent this, a 45 vertical slot 51 is formed in the said plunger which coacts with a pin 52 formed on the casing.

When no pressure is admitted to the chamber 37 the plunger 43 is forced by its spring to the position shown in full lines Fig. 1 the arm 50 being brought to the left 50 of the figure by the groove 45 and the bottle guard is opened (see Fig. 8). If pressure is now admitted to the chamber 37 the plunger rises and by means of the cam groove causes the pin 46 and with it the arm 50 to move to close the guard 39, at the same time the pad 55 33 is pressed onto the bottle and firmly holds same in position.

The operation is as follows:—The disk valve 4 is first placed in the position at *x* Fig. 3 and the rotary frame 6 in a position opposite to that shown in Fig. 1 60 and a bottle placed therein. In this position of the valve 4, water enters the chamber 2 from the supply 16 and runs to waste through waste pipe 18, and at the same time syrup enters the chamber 3 from the supply pipe 21. The valve 4 is now turned to the 65 position shown in Figs. 1 and 3 whereby the water and

syrup supplies and waste are cut off and the gas supply from the pipe 10 opened to the chamber 2 through the port 9 in the valve 4, whereby the gas bubbles up through the water in the chamber 2 and collects at the top thereof aerating the water in so doing. The 70 frame 6 is now rotated through 180° to the position shown in Fig. 1 whereupon the contents of the chambers 2 and 3 are discharged into the bottle through the respective passages 11, 12, 25 30 and 28 under pressure of the gas compressing the air in the bottle until the 75 pressure therein is equal to the pressure of the gas supply. The bottle frame 6 is now turned through another 180° cutting off communication with the supply of aerated mixture and in this position the compressed air and gas in the bottle collect in the neck thereof 80 and the passage 28 comes into communication with a snift port 26 so as to allow the compressed gas to snift off, the bottle is then further turned through another 180° reestablishing communication between the bottle A and the chambers 2 and 3 and permitting more 85 aerated mixture to be forced into the bottle. If some mixture still remains in either of the chambers 2 or 3, the bottle may be turned round again snifting off the pressure therein and receiving more aerated mixture. When all the mixture has been forced into the 90 bottle A the gas passes through the chambers 2 and 3 into the bottle thus further aerating the mixture and establishing a pressure in the bottle equal to that of the gas supply. When the rotary frame 6 is in the position Fig. 1 for receiving the supply of mixture the chamber 95 37 is brought into communication with the gas supply through the passages 13, 14, 30, 31 whereby the pneumatic pad 33 is pressed tightly against the base of the bottle and firmly supports the same. At the same time the plunger 43 is raised which rotates the arm 50 100 and thereby moves the guard 49 to inclose the bottle as shown in dotted lines in Fig. 8. The valve 4 is now turned back to normal position as indicated at *x* which operation cuts off the gas supply, snifts the pressure in the passage 28, and also allows the gas to escape 105 from the pneumatic pad, which opens the bottle guard and the stopper in the bottle A is forced upon its seat and the operation completed.

From the above description it will be seen that by means of the novel combination of the aerating and bottling apparatus the attendant has only to turn the valve of the aerating apparatus and rotate the bottle frame to perform all the necessary operations of aerating and bottling the liquid and that these motions can be conveniently and simply performed by the right 115 and left hands of the operator as he stands at the machine.

What I claim and desire to secure by Letters Patent is:—

1. The improved aerating and bottling apparatus comprising a fixed frame, a chamber on the frame adapted to be filled with water, means for supplying the chamber with water and with gas once in every cycle of operation, a rotary disk valve for controlling the supply of water and gas and delivery of aerated water, cup shaped packers in the valve, a frame for holding a bottle adapted to be rotated in the plane of its longitudinal axis, a second rotary valve having one face on the fixed frame and one face on the bottle frame, cup shaped packers in the valve, and passages adapted to lead aerated water from the chamber to the mouth of the bottle, substantially as described. 120
2. The improved aerating and bottling apparatus com- 125

prising a fixed frame, a chamber in the frame adapted to be filled with water, a second chamber adapted to be filled with syrup, means for supplying the first chamber with water and means for supplying the second chamber with syrup once during every cycle of operations, a gas supply leading to the first chamber, a rotary disk valve for controlling said supplies and delivery of the aerated water, cup shaped packers in the valve, a frame for holding a bottle and adapted to be rotated in the plane of its longitudinal axis, a second rotary valve having one face in the fixed frame and one face on the bottle frame, cup shaped packers in the valve and passages adapted to lead the water and syrup to the mouth of the bottle.

3. The improved aerating and bottling apparatus, comprising a chamber adapted to be filled with water, a second chamber adapted to be filled with syrup, a frame containing a bottle and adapted to be rotated in the plane of the longitudinal axis of the bottle, means for supplying the first chamber with water, means for supplying the second chamber with syrup, a gas supply leading to the first chamber, valves for controlling said supplies, valves and passages adapted to lead said gas supply through the first chamber and through the second chamber to the mouth of the bottle, a bottle guard, means for holding the bottle in position, and means for operating said bottle guard, said

means being actuated by the pressure of the gas supply, substantially as set forth.

4. The improved aerating and bottling apparatus comprising a chamber adapted to be filled with water, a second chamber adapted to be filled with syrup, a frame containing a bottle and adapted to be rotated in the plane of the longitudinal axis of the bottle, means for supplying the first chamber with water, means for supplying the second chamber with syrup, a gas supply leading to the first chamber, valves for controlling said supplies, valves and passages adapted to lead said gas supply through the first chamber and through the second chamber to the mouth of the bottle, a bottle guard, a cup on said frame adapted to receive the mouth of the bottle, a pneumatic pad on said frame for holding the base of the bottle, and means for operating said bottle guard, said means and pneumatic pad being actuated by the pressure of the gas supply, substantially as set forth. 30 35

In witness whereof, I have hereunto signed my name in the presence of two subscribing witnesses.

GEORGE HIGGINSON.
